UNITED STATES PATENT OFFICE.

HORACE K. LYON, OF TULSA, OKLAHOMA.

APPARATUS FOR PRODUCING SULFUR DIOXID.

1,337,561.

Specification of Letters Patent. Patented Apr. 20, 1920.

Application filed July 17, 1919. Serial No. 311,429.

To all whom it may concern:

Be it known that I, HORACE K. LYON, a citizen of the United States, residing at Tulsa, in the county of Tulsa and State of Oklahoma, have invented certain new and useful Improvements in Apparatus for Producing Sulfur Dioxid, of which the following is a specification.

This invention relates to apparatus for producing sulfur dioxid.

The idea involved is to burn crude sulfur ore and convert the sulfur into sulfur-dioxid which is conveyed to a suitable collecting tank, sulfuric acid being made from the sulfur dioxid, in the well known manner.

In carrying out the invention the ore is preferably, but not necessarily, crushed and introduced into a furnace. The furnace is heated by artificial means until the sulfur begins to burn, after which the artificial heat is materially reduced, thus effecting a saving in fuel.

Air is supplied to the burning sulfur in sufficient quantity to produce sulfur dioxid. The fumes or sulfur-dioxid are passed through a heating chamber at a very high temperature. Provision is made for introducing additional air or oxygen into the heating chamber so that any sulfur which may have volatilized may be converted into sulfur-dioxid. Any sulfur which volatizes or condenses and is permitted to escape in such a state would be lost.

The invention will be more readily understood from reading of the following specification and by reference to the accompanying drawings, in which an example of the invention is shown and wherein:

Figure 1 is a longitudinal sectional view of a furnace for carrying out the method,

Fig. 2 is a transverse vertical sectional view of the same,

Fig. 3 is an end elevation, and

Fig. 4 is an elevation of the opposite end.

In the drawings the numeral 1 designates a suitable furnace structure having end plates 2 and 3 respectively, and a top plate 4.

A fire box or combustion chamber 40 is disposed longitudinally of the furnace, a

short distance above the bottom thereof. The fire box is spaced from the side walls of the furnace and the end plate 3, but communicates with a draft opening 5 in the plate 2. A counter-balanced damper 6 normally closing the opening is slideable vertically in guides 7. The bottom of the fire box is rounded and a revolving agitator 8 is journaled in the box, its shaft 9 extending through the plate 3 and carrying a pulley 10 by which it may be driven. A slide-gate 11 at the center of the bottom of the fire box may be withdrawn through the plate 3 to dump the ash into a hopper 12 from which it may be suitably removed.

A hopper 13 on the top 4 is surrounded by a heating jacket 14 having vents 15 at its top. A vertical chute 16 extends from the hopper down to the top 18 of the fire box. A pair of normally closed doors 17 at the bottom of the hopper permit ore to be dropped therebetween, but prevent the escape of fumes from the fire box.

Heating chambers 19 and 20 respectively, are superposed above the box 40, said chambers being spaced apart and spaced from the walls of the furnace as well as being spaced from the top 18 of the box. A flue 21 connects the lower chamber 19 with the fire box adjacent the end plate 3; while at the opposite end of the chamber 19, a flue 22 connects with the chamber 20. The chute 16 extends through the chambers. An outlet flue 23 leads from the opposite end of the chamber 20.

Burners 24 are located under the bottom of the fire box on each side of the ash hopper, and can be supplied with oil, gas or any other fuel. The heat generated by the burners acts directly on the fire box and passes around the same and then passes upward and between the heating chambers, to the jacket 14 and out through the openings 15. By this means the fire box chambers 19 and 20 and hopper 13 are heated to a necessary degree in each instance.

Ore containing sulfur is fed into the hopper 13 and is there heated and dried. The ore is dropped into the chute 16 and reaches the fire box 40 in a warm state. The agita-

tor spreads the ore and the round bottom assists in an even distribution of the same. The temperature in the fire box is high enough to cause the sulfur to ignite and burn. The draft opening 5 is opened by raising the damper 6 and sufficient air is admitted to enable the sulfur to be converted into sulfur-dioxid. This product will pass up through the flue 21 into the lower heating chamber, throughout the length of the latter and into the upper chamber 20 and will be discharged from the latter at its opposite end. It will be seen that the sulfur-dioxid will pursue a circuitous path 15 through the heating chambers.

Great heat is required and after the furnace is thoroughly heated the burners may be cut down to a minimum. There is danger of the sulfur volatilizing and to avoid this an air inlet duct 25 is mounted in the end plate 3 and extends into the chamber 19. This duct has its discharge end curved downward over the flue 21. A rotary damper controls the admission of air to the duct. 25 This duct admits oxygen in sufficient quantity to defeat volatilizing at this point. The high temperature of the sulfur dioxid is maintained throughout its journey through the furnace.

30 Very satisfactory results have been had from ore containing sulfur and gypsum, the former burning and the latter not burning.

What I claim, is:

1. In a furnace for producing sulfur di-
35 oxid direct from ore, a fire box, means for artificially heating the fire box to ignite the ore, the fire box having an air inlet, means above the fire box for preheating the ore and supplying the same to the box, and a
40 heating chamber also above the fire box communicating therewith, said heating chamber being separate from the preheating means.

2. In a furnace for producing sulfur di-
45 oxid direct from ore, a fire box, means for artificially heating the fire box to ignite the ore, the fire box having an air inlet, means above the fire box for preheating the ore and supplying the same to the box, a heating
50 chamber also above the fire box and communicating therewith, said heating chamber being separate from the preheating means, and means for admitting additional air to the heating chamber.

55 3. In apparatus for producing sulfur di-
oxid, a fire box, means for supplying sulfur containing material into the fire box, agitating means within the fire box, a heating chamber arranged near the fire box and spaced therefrom and having means of communication therewith for the passage of the sulfur dioxid, means for introducing a suitable amount of air into the fire box, a furnace structure embodying a jacket sur-
60 rounding the fire box and heating chamber
65

in spaced relation and being free from communication with the interior thereof, and burners arranged within the lower portion of the furnace structure exteriorly of and near the fire box.

4. In apparatus for producing sulfur di-
oxid, a fire box, means for supplying sulfur containing material into the fire box, agitating means within the fire box, a plurality of spaced superposed heating chambers arranged above the fire box, the lower chamber being spaced from the fire box and provided near one end thereof with means of communication with the fire box, means of communication between the ends of the heating chambers which are remote from the first named means of communication, outlet means connected with the opposite end of the upper chamber, means for admitting a suitable amount of air into the fire box, a furnace structure embodying a jacket surrounding the fire box and heating chamber in spaced relation and being free from communication with the interior thereof, and heating means arranged within the lower portion of the furnace structure exteriorly of and near the fire box.

5. In apparatus for producing sulfur di-
oxid, a fire box, means for supplying sulfur containing material into the fire box, agitating means within the fire box, a plurality of spaced superposed heating chambers arranged above the fire box, the lower chamber being spaced from the fire box and provided near one end thereof with means of communication with the fire box, means of communication between the ends of the heating chambers which are remote from the first named means of communication, outlet means connected with the opposite end of the upper chamber, means for admitting air to one end of the fire box which is remote from the means of communication between the fire box and the lower chamber, an air supplying device arranged near the means of communication between the fire box and lower chamber, a furnace structure embodying a jacket surrounding the fire box and heating chambers in spaced relation and being free from communication with the interior thereof, and heating means arranged within the furnace structure near the fire box.

6. In apparatus for producing sulfur di-
oxid, a fire box having a bottom curved in vertical cross section, a rotatable agitator extending longitudinally within the fire box, a plurality of spaced superposed heating chambers arranged above the fire box, the lower chamber being spaced from the fire box and provided near one end thereof with means of communication with the fire box, means of communication between the ends of the heating chambers which are remote from the first named means of communication.

gas outlet means connected with the opposite end of the upper chamber, means for supplying air to the fire box, a hopper arranged above said chambers and having a depending chute extending through said chambers and leading into the fire box, a furnace structure embodying a jacket surrounding the fire box and heating cham-
bers in spaced relation, a jacket surrounding the hopper and having communication ¹⁰ with the first named jacket, and a burner arranged within the lower portion of the furnace structure near the fire box.

5 In testimony whereof I affix my signature.

HORACE K. LYON.
